UNITED STATES PATENT OFFICE.

JOHN A. SEELY, OF NEW YORK, N. Y., ASSIGNOR TO THE WESTERN ELECTRIC COMPANY, OF CHICAGO, ILLINOIS.

MULTIPLE SWITCH-BOARD FOR TELEPHONE-EXCHANGES.

SPECIFICATION forming part of Letters Patent No. 330,067, dated November 10, 1885.

Application filed March 28, 1885. Serial No. 160,424. (No model.)

To all whom it may concern:

Be it known that I, JOHN A. SEELY, a citizen of the United States, residing at New York, in the county of New York and State 5 of New York, have invented a certain new and useful Improvement in Grouping Spring-Jacks and Annunciators for Multiple Switch-Boards, of which the following is a full, clear, concise, and exact description, reference being had to the accompanying drawings, forming a part of this specification.

My invention relates to multiple switch-boards of a telephone-exchange; and it consists in distributing the calling-annunciators 15 of the different subscribers in uniform groups upon the different boards, and in providing extra sets of switches or spring-jacks for each group of annunciators, so that when an annunciator is thrown down a spring-jack in the 20 line may be found always within easy reach and in a given position with respect to the said annunciator. An operator answering the calls of any particular group or groups of annunciators may thus always find at once the 25 answering spring-jack of a subscriber who has sent in a call. Since the groups of annunciators and their corresponding sets of answering spring-jacks are all arranged in the same positions relatively to one another upon 30 all the boards, an operator accustomed to work at one board can work at any other board just as well, so that the operators may be transferred from one board to another from time to time as may be desired.

35 In the drawings, Figure 1 is a front view of a portion of a multiple switch-board illustrative of my invention. Fig. 2 is a front view of the same, the upper portion thereof, which carries the connecting-cords and plugs, being 40 broken away. Fig. 3 is a diagram showing partial sectional views of three multiple switch-boards, with the circuits of two telephone-lines connected therewith, an additional or extra spring-jack being placed in the circuit of each of said lines.

45 As shown in Figs. 1 and 2, each section, 1, 2 3 4, &c., upon the switch-board may contain one hundred spring-jack switches. Thus the board, when full, would contain switches or 50 terminal connections for twelve hundred telephone-lines. The individual annunciators are

placed on the lower part of the board and grouped in sections of twenty-five. Thus each section a' a^2 a^3 a^4 a^5 a^6 on each board may contain twenty-five individual-annunciators 55 and five clearing-out annunciators, as shown in sections a' a^2 of Fig. 1. I preferably place the clearing-out annunciators in a row on the lower part of each section, so that each section contains twenty-five individual or subscriber's drops, as shown in sections a' a^2 of 60 Fig. 1. Eight such boards ordinarily will afford facilities for making the connections and disconnections between twelve hundred telephone-lines.

65 In Fig. 3 of the drawings the circuit of telephone-line d may be traced through the ordinary spring-jacks $e f g$ on each of the boards, and thence through the additional spring-jack h on one of the boards, and thence through the 70 annunciator i to ground. In like manner the circuit of telephone-line k may be traced through spring-jacks $l m n$ on the different boards, and from the spring-jack n to the additional or extra spring-jack o on one of the boards, and 75 thence through an annunciator, p , to ground—that is to say, as shown in the drawings, an individual annunciator is provided for each telephone-line and a spring-jack on each of the boards for each line in the ordinary manner, and in addition extra spring-jacks are provided for the different lines, said extra spring-jacks being arranged in groups $b' b^2 b^3$, &c., to correspond to the individual annunciators on the different boards. There will 80 thus be a switch in each line on each board, an individual annunciator in each line at one of the boards, and an extra spring-jack in each line placed near the individual annunciator of the line, the extra spring-jacks of the 85 different groups of annunciators being placed preferably in the same relative positions, respectively, to their corresponding annunciators upon the different boards.

As is well known in multiple-switch-board 95 systems of telephone-exchange the subscribers are divided, usually, into as many groups as there are switch-boards. Thus, in case there are twelve hundred subscribers and eight boards, the calls for connections of subscribers whose lines are numbered from 1 to 100 150 would be answered at the first board, for

example. The calls of the next group of one hundred and fifty would be answered at the second board, and so on. The calls of the subscribers whose lines are numbered from 5 1050 to 1200 would be assigned to the last board, or board No. 8. When a subscriber sends current to his telephone-line and throws down his shutter, the switchman at the board where the shutter is placed inserts a plug in 10 the spring-jack of his line, and thus places himself in telephonic communication with the said calling subscriber. This I term the "initial" connection. The "calling" subscriber is the one who has thus sent in a signal to the 15 central office. After the initial connection is made, the calling subscriber tells the operator what other subscriber he wants to talk with. The subscriber thus asked for is usually spoken of as the "called" subscriber. 20 The operator having received the order of the calling subscriber, signals the subscriber wanted and makes the necessary connections.

The great advantage of multiple-switch-board systems over all other systems is due 25 principally to the fact that the operators at the different boards do their work independently of one another—that is to say, the operator, we will say at board 1, is able to connect any one of the one hundred and fifty lines 30 assigned to him with any other of the said one hundred and fifty lines, or, in short, with any other of the twelve hundred lines belonging to the exchange.

There are various test systems in use by 35 which an operator can determine whether the line of a subscriber called for is busy or connected at another board. These test systems form no part of my invention, and require therefore no further description. In order, 40 however, that the state of the art may be understood, the following United States Letters Patent are cited: No. 252,576, granted Leroy B. Firman, January 17, 1882; No. 308,315, granted Milo G. Kellogg, November 18, 1884; 45 No. 305,021, granted Charles E. Scribner, September 9, 1884.

Suppose a shutter, 1, of section a' falls. (See Figs. 1 and 2.) The attendant will at once insert a plug, c , of a pair of cords in the spring-jack 1 of group b' , corresponding to group a' . The same operation takes place with respect to the initial connection with any line when its shutter falls, no matter upon which board the shutter of the line may be placed.

55 As shown in Fig. 3, lines d and k are connected by a pair of cords and plugs at the first board. The manner of making this connection may be stated briefly, as follows: The subscriber wanting a connection sends current 60 over his line d , and the switchman at board 1, seeing shutter i fall, at once makes the initial connection by inserting plug q in spring-jack h , and at the same time throwing down the cam-lever r , thus bringing his telephone 65 into the circuit of telephone-line d . The switchman is thus brought into telephonic communication with the calling subscriber

and is told what connection is wanted. We will suppose that the calling subscriber asks for connection with line k . The switchman will at once insert the other plug of the pair—that is to say, plug s —in spring-jack l of line k , as shown, and by depressing key t send current over line k , thus ringing up the called subscriber. The two lines k and d are thus connected and the switchman restores lever r to the position shown and is ready to attend to the next call. Suppose now that subscriber connected with line k had wanted connection with line d . The switching would be done upon the second board—that is, upon the board upon which is placed the extra spring-jack o and the annunciator p in the circuit of said line k . The initial connection would be made with spring-jack o , while the final connection would be made with spring-jack f . The extra spring-jack h and the individual annunciator i should be placed upon the first board in the same positions relatively as are placed the spring-jack o and individual annunciator p upon the second board. In an exchange of twelve hundred subscribers and eight multiple boards, for example, each board would contain, beside the twelve hundred spring-jacks heretofore used, one hundred and fifty extra or additional spring-jacks b' b^2 b^3 , as shown in Fig. 2 of the drawings, but it will be readily understood by reference to Fig. 3 that the extra spring-jacks on the different boards do not belong to the same telephone-lines. Thus the extra spring-jack h of line d is placed upon the first board, while extra spring-jack o of line k is placed upon the second board; but, as before stated, spring-jack h and annunciator i of the first board may be placed relatively in the same positions as spring-jack o and annunciator p , and in like manner a large number—for example, one hundred and fifty spring-jacks h on one board and one hundred and fifty spring-jacks o upon another board—may be placed relatively in the same positions with respect to their individual annunciators.

The spring-jacks for the connection with the calling subscribers preferably are placed in sections or groups distributed in the same line across the board, as shown. When a large number of lines are connected upon the same board, the cords will not become tangled, since the plugs inserted in the additional or extra spring-jacks will be distributed across the board, instead of being within a small section upon the face of the board, as heretofore.

I claim as new and desire to secure by Letters Patent—

1. In a multiple-switch-board system in which the individual annunciators are distributed in groups upon the different boards, switches for all the lines on each of the boards, and, in addition thereto, sets or groups of switches on the different boards corresponding to the different groups of individual annunciators, each group of annunciators and its corresponding group of switches being placed

relatively to each other in the same position on each of the boards, whereby the manner of answering the subscribers is made uniform upon all the boards.

- 5 2. In a multiple-switch-board system, a spring-jack switch on each board for each line, and additional spring-jack switches, one in each line, for the initial connection, said additional spring-jack switches being distributed 10 on the different boards in uniform groups, and the individual annunciators of the different lines arranged in corresponding groups, substantially as and for the purpose specified.
3. In a multiple-switch-board system, a 15 spring-jack switch on each board for each line,

and additional spring-jack switches, one in each line, for the initial connection, said additional spring-jack switches being distributed on the different boards in uniform groups arranged in lines across the boards, and the individual annunciators of the different lines arranged in corresponding groups, substantially as and for the purpose specified. 20

In witness whereof I hereunto subscribe my name this 13th day of March, A. D. 1885.

JOHN A. SEELY.
